United States Patent

Des. 234,825
Patented Apr. 8, 1975

234,825

NEBULIZER

Donald F. Diedrich, Temecula, Calif., assignor to Hudson
Oxygen Therapy Sales Company, Temecula, Calif.

Filed Oct. 6, 1972, Ser. No. 295,560

Term of patent 14 years

Int. Cl. D24—02; D23—01

U.S. Cl. D83—1 N

FIGURE 1

FIGURE 2

FIGURE 3

FIGURE 4

FIG. 1 is a perspective view of the nebulizer showing my new design;

FIG. 2 is a side elevational view thereof with the side wall liquid holding cup in section;

FIG. 3 is a top plan view of the nebulizer; and

FIG. 4 is a bottom plan view of the nebulizer.

I claim:

The ornamental design for a nebulizer, as shown.
